UNITED STATES PATENT OFFICE

110,749

DESIGN FOR A SCROLL SAW FRAME

Alvin Haas, Peru, Ill.

Application December 24, 1937, Serial No. 73,841

Term of patent 7 years

To all whom it may concern:

Be it known that I, Alvin Haas, a citizen of the United States, residing at Peru, in the county of La Salle and State of Illinois, have invented a new, original, and ornamental Design for a Scroll Saw Frame, of which the following is a specification, reference being had to the accompanying drawing, forming part thereof.

In the said drawing—

Figure 1 is a top plan view of a scroll saw frame embodying my new design;

Figure 2 is a side elevational view of the same;
Figure 3 is a front elevational view of the same;
and

Figure 4 is a rear elevational view of the same.

I claim:

The ornamental design for a scroll saw frame,
as shown.

ALVIN HAAS.
